ROBERT A. FORESMAN, OF MOORE, PENNSYLVANIA, ASSIGNOR TO WESTINGHOUSE ELECTRIC AND MANUFACTURING COMPANY, A CORPORATION OF PENNSYLVANIA.

AIR BOX FOR STOKERS.

Application filed January 3, 1923. Serial No. 610,505.

This invention relates to stoker furnaces above described is of a conventional construction and per se forms no part of my present invention.

5 The forward ends of the air boxes 10 are 55 preferably provided with horizontally-disposed portions 25, upon which is disposed, so as to span the spaces between the tuyère air box 10, a wall-sustaining structure 26. As shown, the wall-sustaining structure 26 60 comprises a plurality of sections 27, which may be cast or otherwise formed of iron, steel or other suitable metal. Each section 27 has a lower pedestal portion 28 of a width equal to the width of the air box 10 65 and an upper table portion 29 in width equal to the distance between the center lines of the retorts. The pedestal portions 28 may, if desired, be made hollow to give greater strength for the weight of metal employed 70 in sections 27. When the sections 27 are assembled one on the forward end 25 of each air box, they present a substantially flat supporting surface for a refractory wall 30 of the character commonly employed in 75 furnaces, and the spaced pedestals 28 constitute bounding walls of the fuel opening 22. The pedestal portions are notched at each side at 31, into which notches plates 32 are adapted to be inserted. A guide plate 33 80 of broad U-shape extends the width of the furnace and projects downwardly and outwardly into the hopper 20. The sections 27 are secured to the guide plate 33 by means of bolts 34 and the outer projecting edges 85 35 of the plates 33 may be secured to the rear wall plates 36 of the hopper 20 by means of bolts 37.

Air-distributing boxes 40 are disposed beneath the inwardly extending ledge of the 90 table portion 29 of the sections 27 and may be secured thereto by means of bolts 41. Each air-distributing box has an inwardly-protruding base portion 43 which rests upon and serves to lock in place by means of a 95 bolt 44 the upper tuyère of a series of tuyères. The base of the air-distributing box has a contour similar to that of the tuyère upon which it rests and is open to receive air from the air box 10 through opening 46 in the tuyère 12 upon which it rests. The upper portion 47 of the air-distributing 100

10 tributing boxes resting upon and receiving air from the tuyère boxes. It has for a further object to secure a more uniform distribution of fuel entering the furnace by providing in the front wall structure diverging 15 or expanding openings from the fuel hopper into the interior of the furnace.

These and other objects of my invention which are more manifest in the further description of my invention may be attained 20 by the employment of the apparatus illustrated in the accompanying drawing in which, Fig. 1 is a fragmentary perspective view of a stoker embodying my invention; Fig. 2 is a view in elevation of the front wall air-distributing box and wall-sustaining structure, looking from the interior of the furnace, certain parts being broken away; Fig. 3 is a view in section of the wall-sustaining and air-distributing box structure 25 taken on a vertical plane including the center line of a tuyère bank; Fig. 4 is a view in side elevation of a wall-sustaining section; and Fig. 5 is a view in front elevation of the section shown in Fig. 4.

25 Referring to the drawings for a detailed description of my invention, I show an underfeed stoker of the multiple retort type having spaced tuyère air boxes 10 upon the side walls 11 of which are disposed series of 30 tuyère plates 12. Retorts 14 are formed between the side walls 11 of the tuyère air boxes, the bottoms of the retorts being formed of plates 15 supported on lugs 16 on the side walls 11. The side walls 11 are suitably supported upon the frame 17 of the furnace, as for example, by means of the angle irons 18. Fuel is supplied to the retorts and tuyères from a hopper 20 by means of rams 21 reciprocated by suitable mechanism 35 through the openings 22 into the furnace. It is to be understood that the apparatus

box 40 protrudes to either side not unlike the letter T and is provided with a plurality of air discharging apertures 48.

The guide plates 33, the wall sustaining sections 27 with the plates 32 carried thereby and the air-distributing boxes 40 are so shaped that the upper portions of the fuel openings 22 flare or expand from the hopper to the interior of the furnace. This is clearly indicated in Figs. 1, 2 and 3. The guide plates 33, the plates 32 carried by the sections 27 and the protruding ends 47 of air-distributing boxes 40 constitute upwardly-extending flaring upper walls of the openings 22. Similarly, the side walls of the pedestals 28 of the sections 27 and the base portions 43 of the air-distributing boxes 40 constitute laterally diverging walls of the openings 22, which lateral walls merge at the center line of the tuyères.

The manner in which the above described structure is employed is readily understood. In brief, the usual stoker parts, having been assembled, the several sections 27 of the wall construction member 26 are set permanently in place and the wall 30 erected thereon. The plates 32 are inserted into the notches 31 and the air-distributing boxes secured in place by bolts 41 and 44, it being understood that tuyères 12 are in place. The guide plate 33 is now secured to each section 27 of the wall-sustaining member. When it is desired to replace any of the air-distributing boxes 40, it is only necessary to release the bolts 41 and 44 and withdraw the air box into the interior of the furnace, a new air box replacing the section removed. Similarly, the plates 32 may be renewed from time to time.

This arrangement permits the renewal of these parts which are subject to high furnace heat and to erosive wear under the continuous forcing of fuel into the furnace without in any way disturbing the front wall 30 of the furnace. There results a saving not only in cost of labor required to replace these parts, but, what is oftentimes more important, a great saving in the time required to make the replacement, reducing the loss occasioned by the closing down of the unit served by the stoker.

Further advantages in operation are derived from the flaring or expanding of the upper portion of the fuel opening 22 in that fuel is readily directed over the uppermost tuyères so that the fuel bed presents a substantially uniform surface throughout the width of the furnace. Thin spots which frequently occur over the upper tuyères of stokers of this type are thus obviated and consequent uneven distribution of air to the fuel bed prevented.

While I have shown my invention in but one form, it will be obvious to those skilled in the art that it is not so limited, but is

susceptible of various other changes and modifications, without departing from the spirit thereof, and I desire, therefore, that only such limitations shall be placed thereupon as are imposed by the prior art or as are specifically set forth in the appended claims.

What I claim is:

1. In an underfeed stoker, a plurality of air boxes and retorts disposed therebetween, 75 wall-sustaining members, each comprising a pedestal portion and a table portion protruding forwardly and rearwardly from the upper end of the pedestal portion, the pedestal portions of the wall-sustaining members 80 standing upon the forward ends of the air boxes, and a furnace wall supported upon said wall-sustaining members.

2. In an underfeed stoker, a plurality of inclined air boxes, retorts disposed therebetween, the forward ends of the air boxes having upwardly-presented horizontal supporting surfaces, wall-sustaining members, each comprising a pedestal portion and a table portion protruding forwardly and rearwardly from the upper end of the pedestal portion, the pedestal portions of the wall-sustaining members standing upon the horizontal supporting surfaces at the forward ends of the air boxes, and a furnace wall supported upon said wall-sustaining members. 85

3. In an underfeed stoker, a plurality of air boxes and retorts disposed therebetween, a permanent wall-sustaining structure supported upon the forward ends of the air boxes and providing fuel-admitting openings into said retorts, a furnace wall supported upon said wall-sustaining structure, and an air conducting and distributing structure detachably secured to the wall-sustaining structure, whereby the air-conducting and distributing structure may be replaced without disturbing the furnace wall. 100 105

4. In an underfeed stoker, a plurality of air boxes and retorts disposed therebetween, 110 a permanent wall-sustaining structure supported upon the forward ends of the air boxes and providing fuel-admitting openings into said retorts, a furnace wall supported upon said wall-sustaining structure, 115 and an air-distributing box communicating with each air box and detachably secured to the wall-sustaining structure, entirely beneath the top thereof.

5. In an underfeed stoker, a plurality of air boxes and retorts disposed therebetween, 120 a series of tuyères carried by each air box, wall-sustaining members, each comprising a pedestal portion and a table portion protruding from the upper end of the pedestal portion, the pedestal portions of the wall-sustaining members standing upon the forward ends of the air boxes, a furnace wall supported upon said wall-sustaining members, and an air-distributing box disposed 125 130

upon the uppermost tuyère of each series of tuyères, said air-distributing boxes being detachably secured to the wall-sustaining members.

- 5 6. In an underfeed stoker, a plurality of air boxes and retorts disposed therebetween, a series of tuyères carried by each air box, wall-sustaining members, each comprising a pedestal portion and a table portion protruding from the upper end of the pedestal portion, the pedestal portions of the wall-sustaining members standing upon the forward ends of the air boxes, a furnace wall supported upon said wall-sustaining members, and an air-distributing box disposed upon the uppermost tuyère of each series of tuyères, said air-distributing boxes communicating with the air boxes through the said uppermost tuyère and detachably secured to the wall-sustaining members.

10 7. The combination with a stoker having a plurality of tuyère air boxes spaced to form retorts therebetween, of a member supported upon the forward end of each air box, said member comprising a pedestal portion and an extended wall-supporting portion extending frontwardly and rearwardly of the pedestal portion, and a furnace wall supported upon said extending portions.

15 8. The combination with a stoker having a plurality of tuyère air boxes spaced to form retorts therebetween, of a member supported upon the forward end of each air box, said member comprising a hollow pedestal portion and an extended wall-supporting portion extending frontwardly and rearwardly of the pedestal portion, and a furnace wall supported upon said extending portions.

20 9. The combination with a stoker having a plurality of tuyère air boxes spaced to form retorts therebetween, of a T-shaped member supported upon the forward end of each air box, said member comprising a lower pedestal portion in width substantially equal to the width of an air box and an upper wall-supporting portion in length substantially equal to the distance from the

center line of one retort to the center line of an adjacent retort and in length substantially equal to the thickness of the wall, and a furnace wall supported upon said upper portion of said members.

25 10. The combination with a stoker having a plurality of tuyère air boxes spaced to form retorts therebetween, of wall-sustaining structure comprising sections having pedestal portions resting upon the forward ends of the air boxes and table portions protruding forwardly and rearwardly from the pedestal portion, and plates carried by the pedestal portions of adjacent sections and overlying the retorts.

30 11. The combination with a stoker having a plurality of tuyère air boxes spaced to form retorts therebetween, of sectional wall-supporting and auxiliary air box structures, said wall-supporting structure comprising a plurality of table-like sections, each section having a pedestal portion supported upon the forward end of an air box, and a table portion protruding from the upper end of said pedestal portion, said auxiliary air box structure comprising a plurality of hollow castings, each casting being removably secured to one of said table-like sections along the entire length of said table-like section.

35 12. The combination with a stoker having a plurality of tuyère air boxes spaced to form retorts therebetween, of sectional wall-supporting and auxiliary air box structures, said wall-supporting structure comprising a plurality of table-like sections, each section having a pedestal portion supported upon the forward end of an air box, and a table portion protruding from the upper end of said pedestal portion, and said auxiliary air box structure comprising a plurality of hollow T-shaped castings, each casting being removably secured to one of said table-like sections.

40 In testimony whereof, I have hereunto subscribed my name this 28th day of December, 1922.

ROBERT A. FORESMAN.

upon the uppermost tuyère of each series of tuyères, said air-distributing boxes being detachably secured to the wall-sustaining members.

5 6. In an underfeed stoker, a plurality of air boxes and retorts disposed therebetween, a series of tuyères carried by each air box, wall-sustaining members, each comprising a pedestal portion and a table portion protruding from the upper end of the pedestal portion, the pedestal portions of the wall-sustaining members standing upon the forward ends of the air boxes, a furnace wall supported upon said wall-sustaining members, and an air-distributing box disposed upon the uppermost tuyère of each series of tuyères, said air-distributing boxes communicating with the air boxes through the said uppermost tuyère and detachably secured to the wall-sustaining members.

10 7. The combination with a stoker having a plurality of tuyère air boxes spaced to form retorts therebetween, of a member supported upon the forward end of each air box, said member comprising a pedestal portion and an extended wall-supporting portion extending frontwardly and rearwardly of the pedestal portion, and a furnace wall supported upon said extending portions.

15 8. The combination with a stoker having a plurality of tuyère air boxes spaced to form retorts therebetween, of a member supported upon the forward end of each air box, said member comprising a hollow pedestal portion and an extended wall-supporting portion extending frontwardly and rearwardly of the pedestal portion, and a furnace wall supported upon said extending portions.

20 9. The combination with a stoker having a plurality of tuyère air boxes spaced to form retorts therebetween, of a T-shaped member supported upon the forward end of each air box, said member comprising a lower pedestal portion in width substantially equal to the width of an air box and an upper wall-supporting portion in length substantially equal to the distance from the

center line of one retort to the center line of an adjacent retort and in length substantially equal to the thickness of the wall, and a furnace wall supported upon said upper portion of said members.

25 10. The combination with a stoker having a plurality of tuyère air boxes spaced to form retorts therebetween, of wall-sustaining structure comprising sections having pedestal portions resting upon the forward ends of the air boxes and table portions protruding forwardly and rearwardly from the pedestal portion, and plates carried by the pedestal portions of adjacent sections and overlying the retorts.

30 11. The combination with a stoker having a plurality of tuyère air boxes spaced to form retorts therebetween, of sectional wall-supporting and auxiliary air box structures, said wall-supporting structure comprising a plurality of table-like sections, each section having a pedestal portion supported upon the forward end of an air box, and a table portion protruding from the upper end of said pedestal portion, said auxiliary air box structure comprising a plurality of hollow castings, each casting being removably secured to one of said table-like sections along the entire length of said table-like section.

35 12. The combination with a stoker having a plurality of tuyère air boxes spaced to form retorts therebetween, of sectional wall-supporting and auxiliary air box structures, said wall-supporting structure comprising a plurality of table-like sections, each section having a pedestal portion supported upon the forward end of an air box, and a table portion protruding from the upper end of said pedestal portion, and said auxiliary air box structure comprising a plurality of hollow T-shaped castings, each casting being removably secured to one of said table-like sections.

In testimony whereof, I have hereunto subscribed my name this 28th day of December, 1922.
